Primary Examiner — Joseph Kukella*Assistant Examiner* — Lavon M. Amerson(74) *Attorney, Agent, or Firm* — Faegre Drinker Biddle & Reath LLP(57) **CLAIM**

We claim the ornamental designs for the muffler, as shown and described.

DESCRIPTION

FIG. 1 is a right front perspective view showing the new design for a muffler;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The portions of the muffler shown in broken lines form no part of the claimed design.

1 Claim, 6 Drawing Sheets(56)
